UNITED STATES PATENT OFFICE.

ANTONIO BENOIT, JOSEPH LUCIEN MATHIEU, AND HENRI HORMISDAS DUCHESNE,
OF MONTREAL, QUEBEC, CANADA, ASSIGNORS TO BENOIT & MATHIEU, OF MON-
TREAL, CANADA.

AMPLIFIER.

Application filed April 22, 1921. Serial No. 463,715.

To all whom it may concern:

Be it known that we, ANTONIO BENOIT, British subject, JOSEPH LUCIEN MATHIEU, British subject, and HENRI HORMISDAS DUCHESNE, citizen of the United States of America, residing at #195 St. Timothé Street, in the city of Montreal, in the Province of Quebec, in the Dominion of Canada, have invented certain new and useful Improvements in Amplifiers; and we do hereby declare that the following is a full, clear, and exact description of the same.

The present invention relates to improvements in amplifiers; and it consists in providing an amplifier having a continuous and graduated taper beginning at the base of the tone arm and terminating at the mouth, the opening of said amplifier being preferably similar in shape to the base, and gradually enlarging in the shape of an oval.

By reason of this gradual taper, the vibrations or sound waves will flow smoothly, and will be gradually amplified by graduated and even sides, thus eliminating sharp corners or abrupt angles.

The invention will be better understood with the aid of the following description and accompanying drawing, in which:

Figure 1 is a side vertical sectional view of the amplifier adapted to a talking machine.

Figure 2 is a cross section on line 2-2 of Figure 1.

Figure 3 is a cross section on line 3-3 of Figure 1.

Referring to the drawing:

1 is a talking machine casing or cabinet, and 2 is the usual hinged cover. A partition 3 is provided in the upper portion of the cabinet on which are mounted the tone arm 4 and the turn table 5, the former bearing the reproducer, and 6 is the usual motor which is secured below said partition 3 and which actuates the turn table.

Below said partition 3 is provided the amplifier 7, one end of which projects through the opening 8 in said partition 3, and fits snugly into the bearing 9 of the tone arm 4.

A flange 10 is provided on said amplifier which rests against the under side of said partition 3 and by means of which the amplifier may be rigidly secured. The amplifier is preferably curved so as to avoid contact with the motor 6.

The amplifier at its meeting end with the tone arm has approximately the same internal diameter as the tone arm outlet, and then gradually tapers in vertical section to its mouth. The taper in horizontal section is more pronounced than the vertical taper, and gradually extends horizontally at a more pronounced angle, thus causing the amplifier to take an oval shape which gradually flattens as it nears its mouth.

What we claim as our invention is:—

A sound amplifier for talking machines having a cross-section from end to end in the form of a closed curve and comprising a throat, and a bell extending substantially horizontally forward and at an angle therefrom; said throat being gradually tapered both horizontally and vertically from a point adjacent its free end, where it is of circular section, to the point where it merges into the bell, the horizontal taper gradually assuming a more pronounced angle than the vertical taper between said free end and said merging point so that an elliptical section is thereby produced having a horizontal major axis of gradually increasing length; said bell having a continuous gradual taper from said merging point to its free end or mouth both horizontally and vertically, the horizontal taper being relatively more pronounced as compared with the vertical taper than the horizontal taper in the throat portion.

Signed at Montreal, Quebec, Canada this 26th day of March 1921.

ANTONIO BENOIT.

JOSEPH LUCIEN MATHIEU.

HENRI HORMISDAS DUCHESNE.
